UNITED STATES PATENT OFFICE.

GEORGE A. BERLINGHOF, OF LINCOLN, NEBRASKA.

COMBINED PARTING AND WEATHER STRIP.

Application filed October 14, 1926. Serial No. 141,535.

This invention relates to a combined parting and weather strip for use between the outer and inner sashes of windows, and has for its principal object to provide strips which may be conveniently and economically produced of sheet metal, and will be so connected with the sashes that it will operate to advantage as a weather strip and will prevent shaking or vibration of the sashes from effects of winds or air drafts.

The invention includes an elongated, metallic sheet bent transversely to provide a hollow body to be interposed between the vertical parts and upper horizontal parts of the sash, said metallic sheet also being bent to provide recesses for receiving certain guide-strips carried by the movable sashes, whereby dust and air drafts will be excluded, and undue vibration prevented. The novel and useful features of the invention are fully described and claimed herein, and are illustrated by accompanying drawings, wherein Fig. 1 is a horizontal section on line 1—1 of Fig. 6. Fig. 2 is a vertical section on line 2—2 of Fig. 6. Fig. 3 is a perspective view showing one of the guide-strips for a sash. Fig. 4 is a perspective view showing a part of a metallic sheet bent transversely to provide parts of the device. Fig. 5 is a perspective view showing a part of a guide-strip, and Fig. 6 is a view of a window and frame in side elevation.

Referring now to the drawings for a more particular description, the invention is shown and described in connection with conventional parts of a window frame, such as the vertical pulley-stile 7, the sash-stops 8 for the movable, outer sash 9 and inner, movable sash 10, also in connection with the horizontal head-piece 11 for the upper part of the frame.

In order that the objects first mentioned may be attained, the device, in part, consists of an elongated, metallic sheet bent transversely upon itself adjacent to its longitudinal edges to provide a pair of bearing-members 12 and 13 and a pair of reinforcing parts 14 disposed approximately parallel with the bearing-members, and bent from the parts 14 at approximately right-angles to form a pair of brace-members 15, the middle part of said sheet being bent out-

wardly from the brace-members 15 to form a hollow body 16 and a pair of recesses 17 disposed at the sides of said body, approximately parallel with and opening at the edges of said bearing-members.

The hollow body is preferably of rectangular form in cross-section, its particular form, however, not being important except that it provides walls for the recesses 17 which are provided with, approximately, parallel walls. Numeral 18 indicates a sleeve which is disposed between the outer wall of the hollow body and the frame-member or pulley-stile 7; and at 19 is indicated a screw or keeper which traverses the outer wall of the hollow body 16 and the sleeve and engages the frame 7, and it will be understood that any suitable number of sleeves and keepers may be used for securing the device to the frame-member 7, between the sashes.

Numerals 20 indicate a pair of guide-strips, each being secured to the side of a sash and having a wing *a* engaging in a recess 17. While broken away parts are shown in the drawing it will be understood that the length of the guide-strips correspond to the length of the sashes, the length of each combined parting and weather strip being equal to the length of the pulley-stiles or frames 7.

As thus described the bearing-members 12 and 13 are reinforced by members 14, this being of advantage for resisting stresses directed thereto by the sashes which may slide upwardly or downwardly in engagement with said members 12 and 13.

The brace-members 15 operate to resist stresses when directed thereto by the keepers or screws, and the sleeves 18 prevent bending or buckling of the hollow body 16 when the screws or keepers 19 are secured to the pulley-stile or frame, and in operation, the device prevents movements of air currents to advantage, and since the guide-strips carried by the window sashes engage in the recesses undue vibration of the windows is prevented.

Having described construction and operation relating to the vertically disposed parts of a window, a particular description of the upper, horizontal parts will not be required. The device is secured to the up-

per part of the frame or head-piece 11 by means of screws or keepers 19' which traverse the hollow body 16' and sleeves 18' for engaging in the head-piece.

5 The device is provided with a single recess 17' which is sufficient for effective operation for the reason that the outer sash 9 when moved upwardly normally remains in engagement with the head-piece and no protection against wind, weather or vibration is needed for the inner sash at the upper part of the frame since it is never or very rarely raised upwardly to the head-piece.

15 As best shown in Fig. 2 of the drawings, the parts include an elongated, metallic sheet bent transversely to provide a bearing-member 12' and a reinforcing-member 14', a brace-member 15', a hollow body 16' and a recess 17', the latter being arranged 20 for receiving the wing *a* of a guide-strip 20' which is secured to the horizontal parts of the sash 9, and on account of the construction as described the parts operate to exclude air currents and prevent undue vibration.

25 By referring to Figs. 1 and 2 of the drawings it will be seen that the sashes are provided with grooves *b* which extend longitudinally thereof, the guide-strips being provided with ridges *c* which engage in said grooves, this feature being of advantage for 30 reinforcing said guide-strips so that their wings *a* will normally bear upon the reinforcing-members for effectively excluding air currents.

35 While I have shown and described specific construction, I do not wish to be understood as limiting myself in this respect, and changes in form, size, proportion of parts, and minor details may be made, as found 40 to be of advantage, without departing from the spirit of the invention, said changes to be determined by the scope of the invention as claimed.

I claim as my invention,—

45 1. A combined parting and weather strip for application to window frames and the sashes thereof, comprising a parting strip portion composed of a sheet metal strip bent on a longitudinal line to provide an intermediate channel-shaped body for attachment to a window frame between the sashes thereof and with the open end against the frame, an outer portion of the strip being returned

55 in spaced substantially parallel relation to the outer side of the body to provide a channel at the side thereof and returned abruptly against the outer side of the channel and extending beyond the same to provide a flat bearing surface for the adjacent sash and an anchoring and sealing projection for seating in the window frame, and a guide strip composed of sheet metal having flat edge portions offset from one another and with the intermediate portion of the strip disposed at substantially right angles to the edge portions, the outer edge of the intermediate portion projecting beyond the plane of the outer offset edge portion of the strip and returned upon itself to provide an anchoring and sealing rib adapted to be seated 60 in the side of the adjacent sash, the inner offset portion of the strip adapted for sliding engagement in said channel of the parting strip portion.

65 2. A combined parting and weather strip for application to window frames and the sashes thereof, comprising a parting strip portion composed of a sheet metal strip bent on longitudinal lines to provide an intermediate channel-shaped body for attachment to a window frame between the sashes thereof with the open end against the frame, the outer portions of the strip being returned 70 in spaced parallel relation to the outer sides of the body to provide channels at the sides thereof and returned abruptly against the outer sides of the channels and extending beyond the same to provide flat bearing surfaces for the sashes and anchoring and sealing projections for seating in the window frame, and guide strips for attachment to the inner sides of the sashes and each comprising a sheet metal strip having flat edge portions offset from one another and with the intermediate portion of the strip disposed at substantially right angles to the edge portions, the outer edge of the intermediate portion extending beyond the plane of the outer offset edge portion of the strip and being returned upon itself to provide an anchoring and sealing rib adapted to be seated 75 in the side of the adjacent sash, the inner offset edge portion of the strip adapted for sliding engagement in the adjacent side channel of the parting strip portion.
